Patented May 31, 1921.

UNITED STATES PATENT OFFICE.

EDWARD S. MCKINLAY, OF DENVER, COLORADO.

CARTRIDGE-EXPLOSIVE.

1,379,637.

Specification of Letters Patent. Patented May 31, 1921.

Application filed January 16, 1917, Serial No. 142,705. Renewed October 23, 1920. Serial No. 419,073.

To all whom it may concern:

Be it known that I, EDWARD S. MCKINLAY, a citizen of the United States, residing at Denver, in the county of Denver and State of Colorado, have invented certain new and useful Improvements in Cartridge-Explosives, of which the following is a specification, reference being had therein to the accompanying drawing.

0 This invention relates to improvements in cartridge-like devices, that is to say, devices which comprise receptacles adapted to contain explosive materials and retain the same until said materials are ignited and 5 cause to evolve the gas which effects the bursting of the receptacle.

The object of the invention is to provide a simple receptacle adapted to receive two reagents which are normally separated from 10 each other and which, upon coming into contact, are capable of generating large volumes of highly explosive gas, together with optionally controlled means for causing the reagents to come into contact, and optionally controlled means which, at a later instant, can cause the gas so generated to be exploded.

Figure 1 is a longitudinal section through a body of coal or rock wherein has been placed a set of devices embodying my improvements;

Fig. 2 is a section of the cartridge complete;

Fig. 3 is a cross section taken on the line 15 3, 3 of Fig. 2;

Fig. 4 is a side view;

Fig. 5 is a section of the liquid-carrying plug taken on the line 5, 5 of Fig. 2; and

20 Figs. 6, 7 and 8 show modified forms of carrier or package for the carbid.

Fig. 9 is a cross section of the carbid holder.

Fig. 10 is a diagram of an arrangement of circuits and switches for the control devices.

25 Fig. 11 is a diagram of an arrangement of circuits supported on, or adjacent to the cartridge.

I will describe, somewhat specifically, features of construction and the mode of use of 30 an explosion apparatus which is adapted for use in mining coal; that is to say, for use in breaking down coal masses after they have been undermined and after apertures for the reception of the exploding article have been 35 drilled. But it will be understood that in giving such specific description and illustra-

tion, I am aiming to have my invention fully understood without intending to be limited to the specific matters presented.

In the drawings, 1 indicates the room in 60 a coal mine, 2 the roof or superadjacent rock, 3 the bottom or floor, and 4 the coal still standing in its native bed.

In ordinary procedure, the coal bed is undermined; that is to say, a kerf 5 is formed 65 generally by a mining machine, this kerf extending from five to seven feet under the coal and being from three to six inches in depth, vertically. The face indicated at the line 6 can be regarded as that of a room, 70 such as is formed and extended in "room-and-pillar" mining and further regarded as about twenty-five feet wide, horizontally.

The coal having been undermined as illustrated, the operatives next form "shot" 75 holes; that is to say, with long augers they drill holes 7 approximately parallel to the bottom of the coal. These drillings extend inward to varying depths, according to the requirements of the particular coal formation. Sometimes they incline to the right or to the left, horizontally; sometimes they incline more or less to the vertical. The drill hole illustrated can be regarded as approximately two inches in diameter.

The practice has been to insert in the inner ends of these drill holes charges of powder or cartridges containing powder or dynamite or equivalent explosive. For many 80 reasons, the agencies that have been heretofore used for this purpose have been found very objectionable. And, as above stated, the purpose of this invention is to provide a cartridge which will be in many respects preferable, as will be understood from this 85 description.

8 indicates a tube. It may be formed of a paper composition and will at first be described as if so made. For it are provided two closures 9 and 10, as shown. These are 100 corks suitably cut to tightly fill the ends of the paper tube. The closure 9 is solid and is adapted to be inserted into the end of the tube 8 in such way as to have the joint practically gas and liquid-tight. The closure 10 105 is also adapted to have its outer surface fit perfectly tightly in the end of the tube 8. It is, however, hollow or formed with a chamber 11. This chamber is provided with a charge of water, as shown at 12. The inner 110 wall 13 of the closure is continuous except that at 14 there is a small passage left which

is closed by a stopper 15. The latter is made of wax, paraffin, or equivalent material. When in place, it seals the water chamber with a gas and liquid-tight joint. But it is susceptible of melting, and upon a slight softening thereof, the water is allowed to escape.

16 is a device for holding a suitable quantity of calcium carbid. In Figs. 2, 4 and 9 it is shown as a porous paper tube easily permeable by water; in Figs. 6 and 7 it is shown at 16^a as a paper wrapper or holder which infolds a layer of the carbid in such way that it will be firmly held in position but can permit the access of water. In Fig. 8 the carbid is held in a small fibrous sack 16^b.

At 17 there is an electrical resistance wire, preferably a coil of German silver wire, so placed as to have the closure or water plug 15 within the zone of the heat which it can generate. To the terminals of the resistance element are secured wires 18 and 19 which extend out from the tube and are carried to a current-closing and supplying device at 20 having a circuit closer or switch 21.

At 22, 22 are the terminals of a sparking device. To these are connected the supply wires, 23, 24, the latter extending also toward the supply and controlling devices at 20, these, as an entirety, including a sparking coil at 25.

Coal mines today are almost universally equipped with current-transmitting wires for the purposes of operating motors on locomotives, mining machines, drills, or the like; and to obtain current for the mechanism at 20 it is merely necessary to connect detachable terminals 26, 27, to conductor mains, such as those at 28, 29.

The assembling of the several parts to form the complete cartridge can be done either at the time it is to be used for an explosion or it can be done at earlier times, and they can be kept in stock ready for use.

In assembling them, one of the tubes 8 is taken, and after the plug 9 is tightly inserted at one end, the carrier or holder 16 is introduced into the tube in which it lies loosely. Then one of the chambered plugs 10 is inserted at the opposite end, the chamber being preliminarily filled with water, and the water passage at 14 being tightly closed with a fusible plug 15.

When using it for causing an explosion for the purpose above mentioned, the cartridge is introduced into the inner end of the hole 7, the wires 18, 19, or the cable carrying them, being carefully arranged in the front portion of the drill hole.

Then tampering or packing material 30 is inserted and rammed, or otherwise packed, suitably tight.

65 The circuit closer at 21 is closed and the

current is allowed to pass through the heating device at 17. The first intended effect of the heat so generated is to melt out the fusible plug at 15 which is followed by the flowing of the water out from the cavity in the plug 10 into the main chamber. The water immediately contacts with the carbid in the holder 16 and the generation of acetylene gas commences. It proceeds rapidly and a large volume of gas is soon produced. It may result in the bursting of the walls of the paper tube, but in the work being described this is immaterial, as the gas is confined inside of the tamper at 30. After a lapse of sufficient time for the generation of all the gas, the operator closes the spark circuit. Thereupon, the gas is ignited and exploded with great energy.

If the reagents employed are such as to produce a gas of the character indicated the operation must be effected under circumstances where sufficient oxygen will be provided. The chamber in the main tube 8 can be formed to carry a volume of air; and the volume of water can be such as upon decomposition to provide a volume of oxygen. And when a cartridge is used for blasting coal there will be oxygen in the drill aperture as well as in the surrounding region.

The drawings and diagrams are intended to illustrate the fact that two wires, such as 18 and 19, are to be so arranged, and to be connected with terminal circuits in such way that a direct current can be transmitted over them for heating purposes, and an alternating current for sparking purposes. The switch at 21 can be thrown first, to such position as to permit the current from the supply mains to pass to the heating coil, at which time the spark circuit will be cut out, then thrown to such position that the current from the mains will pass through the primary circuit of the sparking devices while the induced current from the secondary coil will pass to the spark point at 22. It will be understood that in all these respects, modifications can be made, as desired.

Having thus called attention, somewhat in detail, to the application of my invention for the specific purpose above referred to, the following matters are to be noted. In place of the paper tube 8, a metallic pipe can be employed which is preferable where the mines are gaseous. The water can be retained in any of several ways instead of confining it in the chamber 11. A wiring can be substituted by which both the heating and the sparking can be attained by a single circuit.

Nor do I limit my invention to cartridges which are used for the purposes of breaking down coal or rock. Similar explosive agencies can be constructed for ordnance im-

plements, in the manufacture of bombs, and the like.

What I claim is:

1. The herein-described explosive cartridge comprising a main retainer, means for holding within the main retainer two reagents separated from each other but adapted to rapidly produce large volumes of highly explosive gas, means for causing 5 the two reagents to come into contact, and optionally controllable devices within the main retainer for causing the explosion of the gas after it has been evolved therein and acting independently of the last said means, 10 substantially as set forth.
2. The herein-described cartridge comprising a main retainer closed at one end, a removable closure at the opposite end, the retainer being adapted to hold in the chamber 15 therein a gas-evolving reagent and one of the closures being adapted to contain a companion reagent normally separated from the aforesaid reagent, controllable means for causing the reagents to come into contact, and optionally controllable means for igniting the products of reaction after 20 they have been formed.
3. The herein-described explosion cartridge comprising a tube with both ends 25 normally open, a removable closure for each

end of the tube, one of said closures having a water chamber with an orifice adapted to be closed by a fusible closure, the main tube having a chamber containing a material reacting with water to produce volumes of 35 explosive gas, means for causing the fusion of said fusible closure, and means acting independently of the means last aforesaid for causing the explosion of the gas generated in the tube. 40

4. The herein-described inclosed explosive receptacle containing two reagents adapted on contacting with each other to produce volumes of explosive gas within the receptacle, by their reaction, means normally separating the said reagents from each other, optionally controlled means for causing the said reagents to contact with each other and produce volumes of explosive gas, and optionally controlled means acting independently of the means last aforesaid for causing the explosion of said gas after it has been formed in the said receptacle. 45 50

In testimony whereof, I affix my signature, in presence of two witnesses.

EDWARD S. McKINLAY.
